UNITED STATES PATENT OFFICE.

NORBERT JOHA, OF MILWAUKEE, WISCONSIN.

MEASURING INSTRUMENT.

1,142,436.

Specification of Letters Patent. Patented June 8, 1915.

Application filed June 22, 1914. Serial No. 846,629.

To all whom it may concern:

Be it known that I, NORBERT JOHA, a citizen of the United States, residing at Milwaukee, in the county of Milwaukee and State of Wisconsin, have invented certain new and useful Improvements in Measuring Instruments, of which the following is a specification, reference being had to the accompanying drawings.

10 This invention relates to certain improvements in measuring instruments and has relation more particularly to a device of this general character serving as a micrometer; and an object of the invention is to provide 15 a device of this general character having novel and improved means whereby a caliper or the like may be set quickly and accurately to any size in one one-thousandths.

Furthermore, the invention has for its object 20 to provide a novel and improved device of this general character which may be employed with convenience and facility as a gage for wire, drills or the like and which may be also employed as a hook scale.

25 The invention consists in the details of construction and in the combination and arrangement of the several parts of my improved measuring instrument whereby certain important advantages are attained and 30 the device is rendered simpler, less expensive and otherwise more convenient and advantageous for use, all as will be hereinafter more fully set forth.

The novel features of the invention will 35 be carefully defined in the appended claims.

In order that my invention may be the better understood, I will now proceed to describe the same with reference to the accompanying drawings, wherein—

40 Figure 1 is a view, in plan, of a measuring instrument constructed in accordance with an embodiment of my invention, calipers being shown in connection therewith; and Fig. 2 is a sectional view taken substantially 45 on the line 2—2 of Fig. 1.

As disclosed in the accompanying drawings, 1 denotes an elongated body of predetermined dimensions having provided along one of its straight longitudinal marginal portions the linear scale 2, while the opposite straight longitudinal marginal portion is provided with the spaced lugs 3, such lugs, as herein disclosed, being one-quarter of an inch in length and spaced one 50 from the other one-quarter of an inch. One

extremity of the elongated body 1 is provided with the longitudinally disposed open ended slot 4 adapted to slidably receive the shank 6 of the head 7, the longitudinal edges of which are provided with the channels or grooves 8 to accommodate the longitudinal marginal portions of the slot 7. 60

The free extremity of the shank 6 is provided at its transverse center with the longitudinally disposed socket 9 adapted to be 65 engaged by the shank 10 of a micrometer screw, the head 11 of which is positioned within the enlarged inner extremity 12 of the slot 5 and adapted to coact with the shoulders 14 afforded by such enlarged portion 12 whereby it will be readily perceived that axial rotation of the micrometer screw will result in a longitudinal movement of the shank 6 and the head 7 and in order to determine the extent of movement of the shank 6 and the head 7, I provide the head 12 with the vernier 15 and the member 1 with the vernier 16, both operating in a manner which is believed to be self-evident. The head 7 projects beyond the opposite 70 longitudinal edges of the body 1, the extended portion 17 being recessed equal to the spaces between the lugs 3 and coacting with the lugs 3 to afford a means whereby calipers or the like may be quickly and conveniently 75 set, as indicated in Fig. 1 of the accompanying drawings, while the opposite extremity 18 serves as a hook whereby the device may be employed with convenience and facility 80 as a hook scale. It is to be understood that when the device is employed as a hook scale 85 the head 7 is adjusted to bring the extremity 18 in contact with the adjacent end of the body 1. It is to be further observed that the extended portion or extremity 18 projects a 90 sufficient extent laterally of the body 1 as to permit the device to be employed as a hook scale.

By the term "hook scale," hereinbefore employed, is intended a measuring instrument provided with a projection adapted to overlie the edge of an article to be measured whereby no particular skill is necessary to position an end of the scale proper flush with the edge of the article to be measured. 100

When it is desired to employ my improved device, as herein disclosed, as a gage for wire, drills or the like, it will be perceived that the inner surface of the head 7 and the adjacent end of the body 1 are employed in 105 110

a manner which is believed to be self-evident to those skilled in the art to which my present invention appertains.

From the foregoing description, it is thought to be obvious that a measuring instrument constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

20 I claim:

1. A device of the character described comprising an elongated member provided with equidistantly spaced lugs along one longitudinal edge, the spaces between the lugs being equal to the length of the lugs, a head slidably mounted upon one extremity of the elongated member, said head being provided in one end with a recess of a length equal to the length of a lug of the member, and means for imparting movement to the head.

2. A device of the character described comprising an elongated member provided with equidistantly spaced lugs along one longitudinal edge, the spaces between the lugs being equal to the length of the lugs, a head slidably mounted upon one extremity of the elongated member, said head projecting beyond the opposite longitudinal edges of the elongated member, one end of the

head being provided with a recess of a length equal to the length of a lug of the member.

3. A device of the character described comprising an elongated member provided with equidistantly spaced lugs along one longitudinal edge, the spaces between the lugs being equal to the length of the lugs, a head slidably mounted upon one extremity of the elongated member, said head projecting beyond the opposite longitudinal edges of the elongated member, one end of the head being provided with a recess of a length equal to the length of a lug of the member, and means for imparting movement to the head, the longitudinal marginal portion of the member opposite to the lugs being provided with a linear scale.

4. A device of the character described comprising an elongated body provided with an open-ended slot in one extremity, the inner end portion of said slot being enlarged, a head provided with a shank, said shank being adapted to be accommodated within the slot and provided with an axial socket, and a micrometer screw, the head whereof is adapted to be positioned within the enlarged portion of the slot, while the shank of the screw is in threaded engagement with the socket of the shank of the first-named head whereby said head may be adjusted relatively to the adjacent extremity of the elongated body.

In testimony whereof I hereunto affix my signature in the presence of two witnesses.

NORBERT JOHA.
